UNITED STATES PATENT OFFICE.

HENRY M. CRANE, OF NEW YORK, N. Y., ASSIGNOR TO WESTERN ELECTRIC COMPANY, OF CHICAGO, ILLINOIS, A CORPORATION OF ILLINOIS.

ELECTROMAGNETIC LOCKING-SWITCH.

No. 828,090.

Specification of Letters Patent.

Patented Aug. 7, 1906.

Application filed May 9, 1904. Serial No. 207,026.

To all whom it may concern:

Be it known that I, HENRY M. CRANE, a citizen of the United States, residing at New York, in the county of New York and State of New York, have invented a certain new and useful Improvement in Electromagnetic Locking-Switches, of which the following is a full, clear, concise, and exact description.

My invention relates to an electromagnetic locking-switch; and its object is to provide an improved device which will be reliable and certain in its action and which will require a minimum amount of current for its operation.

15 I will describe my invention particularly by reference to the accompanying drawings, and the parts, improvements, or combinations which I regard as novel will be pointed out in the appended claims.

20 In the drawings, Figure 1 is a view in elevation of my improved locking-switch, a portion of its containing-case being shown in section. Fig. 2 is a rear view. Fig. 3 is a diagram illustrating electrical connections. Fig. 4 is a view similar to Fig. 1 with the parts in an alternative position. Fig. 5 is a sectional view on line 5-5 of Fig. 2.

25 The same letters of reference are used to designate the same parts in each of the figures of the drawings.

30 The switch-lever *a*, carrying a spring-contact *b*, is pivoted at *a'* to the end of one arm of an L-shaped iron yoke-piece *c*. This switch is connected with the plunger or push-button *d*, by which it may be actuated. When the plunger is pushed in, the spring-contact *b* is forced against a contact-anvil *b'*. The contact thus made is arranged to complete the circuit of a locking-magnet *e*.

35 The armature *f* of the magnet is pivoted at *f'* to the lower end of the yoke-piece *c* and extends in a direction to meet the free end of the switch-lever *a*. The core of the magnet *e* is mounted upon the yoke-piece *c*, and the magnetic circuit thereof includes the armature-lever *f* and the switch-lever *a*, which is made of magnetic material and acts as a return pole-piece.

40 The inner face of the switch-lever is beveled at *a''*, and when the armature stop-lever *f* is attracted by the magnet *e* its end engages this beveled portion *a''* of the switch-lever, whereby the switch-lever is not only prevented from being retracted, but is actually

55 pressed toward the contact-anvil *b'* against the tension of the spring *g*. When the armature stop-lever *f* is in its normal position, unattracted by the magnet *e*, it rests against the head of a supporting-pin *h*, the shank whereof passes through a hole in the armature and is secured in the end of the magnet- 60 core.

65 The circuit connections are shown in Fig. 3, where the application of my improved self-locking switch to the control of a signal-circuit is illustrated. The circuit from battery *k* includes a lamp-signal *m* and the normally closed contacts of an interrupting-key *n* and is controlled by the contacts *b b'* of the self-locking switch, the circuit also including the winding of the electromagnet *e* of said 70 switch. When the push-button *d* is pressed, the switch-lever *a* is moved from the position shown in Fig. 1 to the position shown in Figs. 4 and 5, closing the spring-contact *b* against its anvil *b'*, and thus completing the circuit 75 from the battery through the magnet *e* and also through the signal device *m* at the distant point. The magnet *e* being excited by current in this circuit draws up its armature *f*, bringing the end of said armature into 80 engagement with the beveled face *a''* of the switch-lever *a*. The switch-lever is thus locked in its actuated position, and the signal *m* will be continuously displayed, subject 85 only to the control of the interrupting-switch *n*. When the switch *n* is opened, the circuit will of course be interrupted, and the electromagnet *e* being no longer excited will allow 90 its armature to drop back, thus permitting the switch-lever *a* to be returned to its normal position by the spring *g*.

95 An arrangement such as that shown in Fig. 3 will be useful, for instance, as a hotel annunciator system, where the lamp-signals, with their interrupting-switches, will be located at a central point, with locking-switches, such as herein described, in the different rooms to control the respective signals.

100 It will be readily understood that the device of my invention will require but a very slight amount of current to operate the locking mechanism. The actual movement of the switch parts to their actuated position is brought about manually, so that the only part to be moved by the electromagnet is 105 simply the armature stop-lever *f*, and when

this armature is drawn up it forms a complete magnetic circuit with the switch-lever *a*, with which it is engaged. The arrangement of the stop-lever to engage a beveled 5 face of the switch-lever is advantageous, not only in that the attractive movement of the armature assists in pressing the switch-contact *h* against its anvil, but when the magnet is deenergized the pressure of the beveled 10 face of the switch-lever against the end of the armature will serve to return the armature positively to its normal position.

I claim—

1. In a self-locking switch, the combination with an electromagnet, of a return pole-piece therefor, a lever pivoted upon said pole-piece, a push-button for moving said lever, switch-contacts closed by said lever when moved by said push-button, and an armature 15 for said magnet pivoted to said pole-piece and adapted when attracted to abut against said lever to hold the same in its actuated position.
2. In a self-locking switch, the combination with a switch-lever, and means for actuating the same, said switch-lever carrying a contact part on one side and having a beveled face on the other side, of an electromagnet and a circuit therefor controlled by said contact, and an armature for said electromagnet, adapted when attracted to engage the beveled face of said switch-lever, whereby the contact is held closed.
3. The combination with an L-shaped iron yoke-piece, of a switch-lever pivoted at one end of said yoke-piece, a contact part carried by said switch-lever, a contact-anvil against which said contact part is pressed when the switch-lever is actuated, an armature forming a stop-lever pivoted at the other end of said yoke-piece, said switch-lever having a beveled face adapted to be engaged by the end of the armature when drawn up, and an electromagnet having its core mounted 40 upon said yoke-piece in position to draw up the armature stop-lever when the magnet is excited, said switch-lever and armature 45

meeting to complete a magnetic circuit, whereby the switch is held in its actuated position by a minimum attractive force of said electromagnet. 50

4. The combination with an electromagnet, of a yoke-piece at the heel of the core thereof, a switch-lever and an armature for said electromagnet both pivoted to said yoke-piece and having their free ends meeting to complete a magnetic circuit, and a contact adapted to be actuated by said switch-lever, the armature being adapted when attracted to engage said switch-lever and lock the 60 same in its actuated position, substantially as set forth.

5. In a self-locking switch, the combination with an electromagnet, of a return pole-piece therefor, a switch-lever pivoted at one 65 end of said pole-piece, a push-button mechanically united with said lever to move the same, contacts closed by said member when moved outwardly by said push-button, and an armature for said magnet pivoted to the 70 other end of said pole-piece, the free end of said armature when attracted abutting against the inner face of the free end of said lever to maintain the lever in its actuated position.

6. In a self-locking switch, the combination with an electromagnet of a switch-lever made of magnetic material and constituting a return pole-piece for said magnet, an armature for the magnet, said armature being engaged by said switch-lever and normally held thereby in its unattracted position, and a push-button adapted to move said switch-lever to permit of the movement of the armature, said armature when in its attracted position being adapted to prevent the return movement of said switch-lever. 80 85

In witness whereof I hereunto subscribe my name this 6th day of April, A. D. 1904.

HENRY M. CRANE
